Attorney

UNITED STATES PATENT OFFICE.

JOHN H. BUSCHER, OF WASHINGTON, DISTRICT OF COLUMBIA.

CUE-TIP HOLDER.

Application filed August 23, 1923. Serial No. 658,860.

To all whom it may concern:

Be it known that I, JOHN H. BUSCHER, a citizen of the United States, residing at Washington, in the District of Columbia, 5 have invented certain new and useful Improvements in Cue-Tip Holders, of which the following is a specification.

In carrying out the present invention it is my purpose to provide a holder for the 10 tips of pool cues wherein these tips may be attached to or removed from the cues in a novel, simple and expeditious manner, the nature of the same being such as to permit of the attachment of a tip to the cue without the usual necessity of applying a compressor tool thereto which necessitates the 15 setting aside of the cut for a certain length of time until the tip has become properly secured to the cue and therefore prevent the 20 cue from being used during this time.

The primary object of my invention is the provision of a holder for cue tips that is extremely simple of construction and one that may be manufactured and marketed at 25 extremely small cost and that may be operated by those unskilled in the art, this holder embracing at the same time the desired features of efficiency and durability and one that will maintain the tip in positive secured relation to the cue.

With the above and other objects in view as the nature of the invention is better understood, the same comprises the novel form, combination and arrangement of parts set 35 forth in the following detailed specification, shown in the accompanying drawing and claimed.

In the drawing wherein like reference characters indicate corresponding parts 40 throughout the several views,

Figure 1 is an elevational view of a cue equipped with my novel cue tip holder,

Figure 2 is an enlarged detail cross section thereof,

Figure 3 is a transverse section taken substantially upon the line 3—3 of Figure 2,

Figure 4 is a view similar to Figure 2 in a slightly modified form of the invention, and

Figure 5 is a perspective of the cue tip per se that is employed in conjunction with my novel holder.

Now having particular reference to the drawing, 5 designates a well known form of pool cue that is reduced at its upper end

and screw-threaded for providing an attachment post 6.

My novel cue tip holder embodies a tip receiving head 7 preferably of metal and being circular in cross section and being 60 provided at its lower end with a screw-threaded socket for the reception of the screw-threaded post 6 of the cue 5. In the form of the invention shown in Figures 1, 2 and 3, this head 7 is cut away at its upper 65 end within which cut-away portion is adapted to be positioned a clamp section 8 it being noted from a consideration of Figure 2 that this cut-away portion at its lower end is curved for receiving the lower 70 curved portion of the inner side of said clamp section 8, this clamp section adapted to be secured to said head through the medium of a set-screw 9 the head thereof being countersunk within this clamp section for 75 obvious purposes.

Formed within the upper end of a head 7 as well as the clamp section 8 are mating semi-circular cut-out portions for providing a socket for the lower reduced portion 10 of 80 a leather cue tip 11. Immediately above said semi-circular cut-out portions of the head 7 and clamp section 8 the material is bent over to provide flanges 12 which flanges are formed intermediate their ends with inwardly extending V-shaped lugs 13 that bite into the cue tip material as clearly shown in Figure 3 for preventing the accidental 85 displacement of a tip from the holder and for also preventing the turning movement 90 of the tip therein.

In the form of the invention shown in Figure 4 the head 7' is formed at its upper end with an L-shaped cut-out portion for receiving a straight somewhat rectangular 95 shaped clamp section 8' which I believe will be a stronger construction than that shown in Figures 1, 2 and 3, it being of course understood in this connection that other than this change the holder is identical with the holder shown in said Figures 1, 2 and 3.

In view of the foregoing, it will be at once apparent to those skilled in the art that I have provided a highly novel and simplified form of holder for cue tips and one that will meet with all of the requirements for a successful commercial use.

Other modifications may be had without departing from the spirit and scope of the appended claim.

Having thus described my invention, what I claim as new and desire to secure by Letters Patent is:—

A cue tip holder comprising a ferrule having at one end a recess leading in from the side thereof, the inner wall of the recess lying in a plane coincident with the axis of the ferrule, the said ferrule being provided at its end with a semi-circular jaw having an inwardly disposed arcuate flange and a pointed lug provided upon the flange and located midway between the ends thereof and disposed with its point toward the center of the ferrule, a clamp section seated in the recess and completely filling the same, a

screw passing transversely through the clamp section and entering the body of the ferrule, said clamp section being provided at its end with a semi-circular jaw having an inwardly disposed arcuate flange and a pointed lug provided upon the last mentioned flange at a point midway between the ends thereof and having its pointed end disposed toward the axis of the ferrule, the said pointed lugs being aligned diametrically of the ferrule.

In testimony whereof I affix my signature.

JOHN H. BUSCHER.
